BUFFING WHEEL AND METHOD OF MANUFACTURE

John F. White, Bloomington, Ill.

Application November 5, 1936, Serial No. 109,231

11 Claims. (Cl. 51—193)

My present invention pertains to certain features of improvement and benefit and advantage in fabric and similar buffing-wheels and their methods of production, one of the leading 5 aims or prime purposes of the invention being to provide a textile-fabric or analogous buffing or polishing wheel which is amply ventilated and cooled, whereby to increase its useful life and to prevent its unduly rapid wear or deterioration 10 by reason of becoming excessively heated to a point of burning or charring.

Another object of the invention is to manufacture such buffing-wheels in an economical manner so that they may be sold to the trade at a fair 15 and reasonable price in view of the improved service rendered thereby.

Various other factors of advantage incident to the employment of the new invention will become apparent from an understanding of the 20 structural features and functional characteristics of the improved wheel and the steps incident to its production as presented in the following detailed description which should be read in connection with the accompanying illustrations in 25 the associated drawings wherein

Figure 1 is a face view of a fragment of a centrally-perforated, bias, textile-fabric strip used in making the new buffing-wheel;

Figure 2 illustrates the manner of making an 30 endless fabric-member from such a strip composed of overlying layers of the fabric which are creased longitudinally centrally and also charged with a suitable adhesive or cement along their lengthwise central portions;

Figure 3 presents the manner of crimping such 35 an endless body to provide a round fabric-element transversely fluted or corrugated;

Figure 4 shows the fabric-element after a 40 confining ring has been applied thereto and the lateral or side portions of the fabric have been folded over parallel to one another;

Figure 5 portrays complementary dies for 45 pressing and corrugating the inner portion of such open-center, fabric, buffing-wheel member;

Figure 6 is a fragmentary section on an enlarged scale on the curved line 6—6 of Figure 8;

Figure 7 is a central section through a finished 50 buffing-wheel incorporating a number of such fabric-elements; and

Figure 8 is a section on line 8—8 of Figure 7 with the parts viewed in the direction indicated by the arrows.

Figure 9 is a face view of an endless, multi-layer fabric-band perforated after formation into 55 endless condition.

In carrying out the novel and improved method of manufacturing the new buffing-wheels and the fabric elements or members entering into their construction, the first step in forming such fabric parts is to provide an endless fabric-band 11 desirably on the bias and of appropriate width, for example, of about 9½ inches, as by cutting a bias strip of cotton-cloth to correct length and rendering it endless by stitching or otherwise fastening its ends together.

Such endless fabric-band is applied to a pair of suitably-spaced, parallel rollers or drums 12, 12, one or both of which may be power or hand rotated to drive the band around its endless path.

A long strip of bias cotton-fabric 13 of approximately the same width as the band 11 is perforated or slit at intervals along its longitudinal center line at spaced points 14, 14, such holes being about one inch long and one-quarter inch wide with spaces between them of about five-eighths inch.

If desired, the longitudinal center-line of the endless-band 11 may be apertured in like manner, such holes in the strip or band or both being provided for the purpose of facilitating the subsequent bending or folding of the fabric-members along such middle lines.

One end of such centrally-apertured strip 13 is attached to the endless-band 11 in any approved or convenient manner, and, when the rollers or drums 12, 12 are rotated and the band 11 caused to travel around them, as will be readily understood, such fabric-strip 13 is wound thereon in a spiral manner until about ten overlying layers thereof have been applied thereto, all as illustrated in Figure 2.

During such winding of the fabric-strip thereon, a narrow, V-shaped roller 15, by pressing against the center-line portion of the strip indents it in some degree to aid in its later folding along such longitudinal crease.

Also during such application of the strip to the endless traveling band, a roller 16 in contact with its central, length-wise zone applies a layer of cement thereto about one inch wide, the supply 45 of such cement being contained in a reservoir or receptacle 17 into which the applying roller 16 dips.

Whereas the cement-charged, convoluted, creased, endless fabric-member may be made in 50 the manner indicated, it is preferable, however, to have a rubber-belt 18 encircle the rollers or drums 12, 12, on which belt the endless fabric-band 11 is mounted, the belt affording added support for the fabric-strip while it is undergoing 55

application under moderate strain and while it is being charged with the cement.

The cement referred to may be of any suitable character, but it has been found that the following is well adapted for this purpose.

One quart measure of zinc-oxide is dissolved in one quart of water making a thin paste, and to this is added one quart of latex, whereupon the compound is mixed with one gallon of sodium silicate and after standing about twelve hours this will be a creamy solution.

As soon as the desired number of layers of the textile-strip have been thus wound into endless form over the inner endless-band, the combined band and wound strip are removed as a unit from the drums or rollers 12, 12 and placed over a suitable revoluble wheel 18 having transverse grooves 19, 19 across its face, which gives the wheel the appearance of a wide spur-gear.

While such grooved wheel is rotated intermittently or step-by-step by hand or by power, the overlying layers of fabric are forced, tucked or gathered into the successive, parallel surface grooves of the wheel either by hand or by a hand-operated or power-actuated blade or bar 21 which may be raised and then lowered into the grooves as the latter are brought successively and individually into register therewith by the interrupted rotation of the wheel, and, in order that the tucking or folding of the cloth into one groove may not withdraw that previously pleated into the next preceding groove, a second blade or bar 22 occupies such latter groove while the member 21 is feeding the fabric layers into the next groove or pocket, and so the indicated procedure is followed until all of the grooves have been filled by the fabric, it being understood, of course, that the length of the endless-band 11 and the wound layers thereon is such as to extend just entirely around the wheel following the contour of all of the grooves.

Upon the completion of this fabric-gathering operation around its middle section, we have a round body of the fabric layers which is fluted or corrugated by reason of those portions thereof in the forming or shaping grooves and then an endless, flat, metal ring 23 is applied centrally over such fabric-member, the combined cloth and ring are removed from the grooved forming-wheel, and the layers of fabric extending equally from both sides of the confining, metal ring are then folded outwardly into parallelism, as shown in Figure 4, the faces of the outermost fabric layer or stratum being brought into contact with one another.

While in this open-center condition, the partially-completed buffing-wheel fabric-element is placed between two matching dies 24 and 25 each of which on its face toward the companion die has spaced recesses 26 with intervening projections 27 with the recesses of each in register with the projections of the other, whereupon the two complementary dies are forced toward one another, thereby corrugating the inner cement-charged portion of the fabric and also correspondingly corrugating the inner metal-ring, which, of course, is covered by the fabric on both of its sides.

In order that this fabric-member may be properly centered with relation to the dies, one of them is provided with a central, round portion 28 of substantially the size of the hole in, and adapted to receive, the fabric-member, and the other die has a complementary, central recess

29 adapted to receive such part 28 when the dies are brought together.

In thus corrugating the fluted or pleated inner, circular portion of the ring-like fabric-body, no attempt is made to make the corrugations coincide with any particular folds of the fabric, the initial or preliminary fluting on the externally-grooved wheel being merely for the purpose of gathering in the excess fabric at the inner part of the member.

When the cement-laden, inner, annular zone of the fabric is corrugated in the manner indicated between the companion dies, the confining, metal ring 23 is also likewise crimped or deformed.

The combined fabric and metal ring buffing-wheel element is removed from between the dies upon their separation and the cement is allowed to harden or set, the wavy metal-ring holding the fabric-layers in their corrugated condition during such setting of the cement.

Having provided a number of such fabric, buffing-wheel members, characterized 30, 30, they are assembled in sidewise registered relation on the interfitting fingers 31, 31 of a pair of complementary hub-members 32, 32 and held clamped between them by a screw or bolt 33 detachably holding them pressed against one another, as indicated in Figures 6, 7, and 8, with the hardened corrugations of the fabric-parts in register or more or less out of register, but in either case providing for satisfactory ventilation between such fabric-components (see Figure 6), one, at least, of the hub-members having apertures 34, 34 for the admission of cooling air to the corrugation conduits or channels.

When such a complete buffing-wheel is rapidly revolved and the article to be polished is applied to its outer surface, the air entering through the apertures 34, 34 and passing out through the corrugation channels into the bodies of the fabric-members maintains them at a temperature which precludes burning, charring, hence unduly rapid wear.

As will be readily understood by those skilled in this art, this invention, defined in the appended claims, which should be interpreted as generally as the state of the prior art permits, is not limited to the precise details set forth and many minor or major modifications may be resorted to without departure from the heart and essence of the invention and without the loss or sacrifice of any of its material benefits and advantages, the dimensions given and the cement composition specified, for example, being subject to change as circumstances dictate.

Instead of providing the fabric-strip 13 with a row of longitudinally-spaced perforations or apertures prior to winding it into endless form with superposed layers, a textile-fabric strip without such perforations may be thus wound into the specified endless shape and then perforated, as shown in Figure 9, in which case the corresponding perforations of the several superimposed strata are in register, and when such an endless fabric member is gathered or corrugated as indicated and bent around the encircling, confining, metal ring, the material at opposite ends of the perforations or slots is merely brought together without overlapping which result will not necessarily be attained if the fabric-strip is first perforated and then wound into endless form.

The importance of this procedure resides in the

fact that it assures an even distribution of the cloth on the ring and consequently extending outwardly therefrom to the periphery of the wheel, thereby contributing to a perfect balance 5 of the wheel which is a prime factor to consider in connection with buffing-wheels operated at a high rate of speed.

Although the use of the endless fabric-band 11 has been referred to and the attachment of the forward end of the fabric-strip 13 thereto, this is not essential, in that the part 11 may be done away with and the advance end of strip 13 attached to the endless rubber-belt 10 by the use of gummed paper or otherwise, which paper 15 can be easily removed when desired, the rubber-belt preventing the cloth from crawling as it is being wound and when cut in straight strips requiring little if any trimming.

In order to facilitate the removal of the finished, endless-member from the two drums or rollers 12, 12 and to aid in instituting the production of a new member thereon, one of such drums 12 may be mounted on a manually-operable eccentric bearing allowing the drum to be 25 adjusted toward and from the other drum, or any other suitable means may be substituted for the same purpose.

I claim:

1. In the making of a textile-fabric buffing-wheel member, the steps of forming a fabric-strip into an endless element of overlying fabric layers, gathering the longitudinal central section of such element into transverse folds, applying a round retaining-ring around the outside of the longitudinally gathered center of said element, folding the fabric over opposite sides of said ring outwardly into substantial parallelism, corrugating laterally at least the inner section of such gathered portion of said open-center fabric-member and said ring, applying cement to the corrugated part of said fabric prior to the corrugating operation, and permitting said cement to harden thus permanently maintaining such section of the buffing-wheel member in corrugated 45 condition.

2. The method presented in claim 1 in which the first step specified therein is performed by making an endless fabric-band, attaching an end of said fabric-strip to said band, and causing said band to travel around its endless path, thereby by applying said fabric-strip thereto in overlying layers.

3. The method presented in claim 1 in which the cement is applied to the central longitudinal zone of said fabric-strip during its winding into endless form.

4. In the making of a textile-fabric, buffing-wheel member, the steps of attaching an end of a fabric-strip to an endless band, feeding said band around its endless path, thereby winding said strip thereon in superposed layers, creasing said strip along its longitudinal center line during such winding, said strip having longitudinally-spaced apertures therethrough along said center line, applying cement along the lengthwise center zone of said strip prior to completion of the winding of the strip, gathering the longitudinal central section of said endless fabric-element into transverse folds, applying a round retaining-ring around the outside of the longitudinally-gathered center of said element, folding the fabric over opposite sides of said ring outwardly into substantial parallelism, corrugating laterally at least the inner section of such gathered portion of

said open-center fabric-element and the ring, and permitting said cement to harden.

5. The method of making a plurality of textile-fabric buffing-wheel members in accordance with the procedure presented in claim 1 and making a 5 buffing wheel therefrom by securing said members together in register side by side in a manner to permit cooling air to flow outwardly through passages provided by the corrugated, cement-hardened parts of the members to cool the wheel 10 during its operation of buffing.

6. An open-center buffing-wheel textile-fabric member comprising in combination a confining-ring, a plurality of overlying textile-fabric layers extended through, folded over opposite sides of, 15 and circularly confined by, said ring, the parts of said layers adjacent to said ring being gathered to absorb fullness, the inner gathered portion of said open-center member being hard and permanently transversely corrugated to provide ventilating 20 passages.

7. In a textile-fabric buffing-wheel, the combination of a plurality of open-center, textile-fabric members arranged side by side in registration, and means to hold said members in the specified 25 relation, each of said members comprising in combination a confining-ring, a plurality of overlying textile-fabric layers extended through, folded outwardly over opposite sides of, and circularly confined by, said ring, the parts of said layers adjacent to said ring being gathered to absorb 30 fullness, the inner gathered portion of each said fabric-member being hard and permanently transversely corrugated to provide ventilating 35 passages.

8. An open-center buffing-wheel textile-fabric member comprising in combination a wavy confining-ring, a plurality of overlying textile-fabric layers extended through, folded over opposite sides of, and circularly confined by, said ring, 40 the parts of said layers adjacent to said ring being gathered to absorb fullness, the inner gathered portion of said open-center member being hard and permanently fluted on at least one side 45 to provide ventilating passages.

9. In a textile-fabric buffing-wheel, the combination of a plurality of open-center, textile-fabric members arranged side by side in registration, and means to hold said members in the specified 50 relation, each of said members comprising in combination a wavy confining-ring, a plurality of overlying textile-fabric layers extended through, folded outwardly over opposite sides of, and circularly confined by, said ring, the parts of said layers adjacent to said ring being gathered to absorb 55 fullness, the inner gathered portion of each of said fabric-members being hard and permanently transversely fluted at least on one side to provide radial ventilating passages.

10. In the making of a textile-fabric buffing-wheel member, the steps of forming a fabric-strip into an endless element of overlying fabric layers, gathering the longitudinal central section of such element transversely, folding the fabric over upon itself along its central longitudinal line into substantial parallelism, fluting laterally at least the inner section of at least one side of such gathered portion, applying cement to the fluted part of the fabric, permitting said cement to harden, 70 and applying means to said fabric to retain the fluting in said fabric during the hardening of said cement.

11. In the making of a textile-fabric buffing-wheel member, the steps of forming a fabric-strip 75

- into an endless element of overlying fabric layers, gathering the longitudinal central section of such element transversely, folding the fabric over upon itself along its central longitudinal line into substantial parallelism, fluting laterally at least the inner section of at least one side of such gathered portion, applying cement to the fluted part of said
- 5

fabric prior to the fluting operation, permitting said cement to harden, and applying means to said fabric prior to said cement application to retain the fluting in said fabric during the hardening of said cement.

JOHN F. WHITE.
